United States Patent

Des. 236,992
Patented Sept. 30, 1975

236,992

GAMEBOARD

Philip V. Pratico, Los Angeles, Calif.
(10541 Rainier St., Sun Valley, Calif. 91352)

Filed Mar. 25, 1974, Ser. No. 454,564

Term of patent 14 years

Int. Cl. D21—01

U.S. Cl. D34—5 SS

The sole figure is an isometric view of a gameboard, showing my new design.

The underside, not shown, is plain and unornamented.

I claim:

The ornamental design for a gameboard, substantially as shown and described.
